UNITED STATES PATENT OFFICE.

ROCKWELL M. MACCORMAC, OF KANSAS CITY, MISSOURI.

PAPER-ROLL HOLDER.

Application filed December 13, 1920. Serial No. 430,136.

To all whom it may concern:

Be it known that I, ROCKWELL M. MACCORMAC, a citizen of the United States, residing at Kansas City, in the county of Jackson and State of Missouri, have invented certain new and useful Improvements in Paper-Roll Holders; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to improvements in roll holders wherein a wound roll is placed upon a distributing core to be intermittently fed off therefrom. The invention is illustrated as applied to a toilet fixture in which a roll holder or part is used to fit into the core of a paper roll and support the roll for use.

One of the objects of the invention is to provide an efficient, durable and inexpensive construction of paper dispensing means which will meet the necessary requirements of a device of the class described.

Among the difficulties heretofore encountered in the practical use of such devices is the ease with which the dispensing devices and the paper rolls can be surreptitiously removed, by unauthorized persons, from the supports to which they are initially secured.

An important objection to some types of such devices is that no provision is made whereby an attendant when calling at any time can remove intact a partially depleted roll and replenish the holder with a new roll because the core of the roll cannot be taken off the fixture until the roll is depleted. The attendant must either call again when the roll has been entirely depleted or must break the depleted roll to remove the same which damaged remnant is then frequently thrown away, resulting in waste.

A more serious objection in other types is that so-called "foreign" rolls may be substituted for the one designed to be used with the dispensing device, which substitute rolls are often of poor quality and of unsuitable

texture, resulting in trouble and dissatisfaction.

An annoying objection in certain types of existing devices is that the ends of successive sheets to be detached from the roll will be found stuck to the face of the roll instead of hanging down free and clear and ready to be grasped.

A further objection is that in some types the paper rolls have large notches or openings in their ends or surface which mar the roll and make it present a disfigured appearance.

My invention contemplates the provision of means whereby all these objections are overcome and desired objects accomplished, and I have also provided means whereby uniform quantities of the paper will be dispensed intermittently.

Means is also provided for generally improving the arrangement, construction and operation of devices of the class herein involved and these features will become apparent by reference to the following description in connection with the accompanying drawings, in which

Fig. 1 is a perspective view of one form of a dispensing device constructed in accordance with my invention.

Fig. 2 is a plan view of the same, the wall bracket plate being shown in section.

Fig. 3 is a detail perspective view of a lock-guard for locking the roll holder and the roll together and for resisting the introduction of unauthorized paper rolls upon the dispensing device.

Fig. 4 is a detail perspective view of a paper-roll-engaging lock-guard having somewhat similar functions to the one shown in Fig. 3.

Fig. 5 is a vertical, longitudinal, sectional view through a device constructed in accordance with my invention, with the paper roll applied and also shown in section.

Fig. 6 is a sectional view on the line 6—6 of Fig. 5, looking in the direction indicated by the arrows.

Fig. 7 is a diagrammatic view of the paper roll ready to be applied to the dispensing device.

Fig. 8 is a diagrammatic view of the paper roll showing the position of the perforations or slits after the outer plies have crept, due to the pull on the paper and to the momentive jar of the holder and roll.

Fig. 9 is a similar view showing the position the paper roll would tend to assume as a normal position after each determined length was dispensed from the roll.

10 Fig. 10 is a similar view showing the position the severance perforations assume in actual practice, and

15 Fig. 11 is a detail perspective view of a device that may be employed for separating the axles and the elements of the split mandrel or core upon which the roll may be mounted.

20 The generic novel features as well as the specific details of construction of sufficient importance will be specifically described hereinafter.

In the drawings I have shown a base plate 1, which may be provided with a peripheral flange 2, if desired, although the plate may 25 be made of relative thick material, in which event the flange 2 may be dispensed with. Outstanding arms 3 and 4 are hinged to the respective ends of the plate 1 and terminate in bearing boxes 5 and 6, formed by 30 bending the ends of the arms back upon themselves in substantially rectangular form, as clearly apparent by reference to Figs. 1 and 2, so that double bearings are provided on each arm for one of the respective axle members of the mandrel or core 35 which supports the paper roll.

If the arms 3 and 4 are formed of sheet metal, I prefer to strike out the metal at the bottom of at least one bearing of each arm, 40 for example, as at 7 in Fig. 5, so as to provide a rest or relatively broad bearing face for the axle which it supports. The bearing openings in the inner walls of the bearing boxes are given an upward elongated form 45 so as to allow passage of the curved axle ends in order to be initially affixed to the respective mandrel drums described herein-after.

The axles, it will be observed, project 50 through the bearing portions 8 and 9 for the box 5, and 10 and 11 for the box 6 and the axle members 12 and 13 are shown as provided with heads 12' and 13' respectively at their outer ends, while their inner ends 55 are oppositely curved and have recess shoulder-engaging portions 14 and 15, the adjacent faces 16 and 17 being curved so that when the two parts are brought together, they will slide one upon the other 60 and cause the shoulders 18 and 19 to interlock, as shown in Fig. 2.

The axle members carry mandrel heads or drums 20 and 21 which, in conjunction with the axles, constitute a core or mandrel 65 upon which the paper roll is to be mounted.

The mandrel members 20 and 21 are provided with flanges 22 and 23 to abut against the ends of the paper roll to be hereinafter referred to and the flanges 22 and 23 are provided with outstanding, resilient projections or lips 24 and 25, which are adapted to contact with the resilient, inwardly projecting lips or lugs 26 and 27 on the arms 3 and 4 so that when the mandrel and paper roll have been rotated through a determined 70 arc, the lips or projections 24 to 27, both inclusive, will act as yielding stops to prevent further rotative movement and also to provide safety stops for flat springs 30 and 31 provided within the boxes 5 and 6 and 80 secured thereto, against which the pins 32 and 33 on the axles 12 and 13 may rub as the axle members or shafts are rotated, the spring friction assisting to retard the rotative movement of the weighted mandrel or 85 core as the length of the paper to be torn off begins to reach the limit of its unwinding movement, and which pins must not be permitted to get altogether past the ends of the flat springs which would block the 90 return movement. To actively assist in the return movement and to position the roll so that the line of perforations will be yielding advanced to a point beyond the line of perpendicular regardless of the center 95 line of gravity as would be established by the weight alone and so that the loose end of the sheet will always drop down from the surface of the roll ready to be grasped for use and also to position the mandrel 100 sections 20 and 21 so that when not supplied with a roll, they will always rest with the roll guide posts 34 and 35 turned to the top somewhat toward the operator and, therefore, in position to readily engage with 105 the roll end slits 36 and 37 when applying the roll, the boxes 5 and 6 are provided with coil springs 38 and 39 respectively, which are wound about the journals of the axle members 12 and 13, one end of each spring 110 being secured to an axle member and the other to a bearing end 5 or 6, as the case may be.

It is desirable to maintain the axle members 12 and 13 in substantially axial alignment to insure perfection of operation and to this end I prefer to provide stop members consisting of inwardly projecting fingers 40 and 41, which are carried by the arms 3 and 4 and which are adapted to rest 120 against the flat faces of the bolt heads 42 and 43 so that when the axle members 12 and 13 are locked together within the paper roll which the mandrel supports, an unauthorized person may not turn the bolts 125 42 and 43 because the turning movement would be opposed by the ends of the fingers 40 and 41; therefore, the device could not be readily removed from the wall or support 130 which holds it.

The plate 1 carries a substantially U-shaped hanger 44, the ends of which project through perforations in the plate 1 and have offset portions by which they are secured thereto, the hanger 44 being for the purpose of holding the nearly depleted roll or portion of a roll which has been removed preparatory to introducing a new roll upon the mandrel or drum members 20 and 21.

As heretofore explained, it is desirable to provide means whereby the paper roll cannot be surreptitiously removed from the holder by an unauthorized person and also whereby an unauthorized or foreign roll may not be used in connection with the dispensing device or roll holder forming the subject matter of this invention, and to this end I have provided a novel construction of lock-guards which are adapted to be carried by a core or mandrel member and which will lock with the roll at the interior and will prevent the roll and one mandrel section from being turned in an opposite direction from the other mandrel section to disengage the axle ends to unlock the same, and these lock-guards will also oppose the introduction of any roll except one especially designed to be utilized in connection with the mechanism herein disclosed.

When so desired lock-guards can be made a part of or be immovably affixed to the inner faces of the mandrel heads and have a roll-recess-engaging locking part projecting rigidly above the peripheral surface of the heads, when to apply a roll to the first mandrel section the roll may be tilted sufficiently for the projection to be received into the roll recess, when the roll and both mandrel sections can then be turned about 90° to the rear and the opposite mandrel head can then be inserted at an angle which will allow its projection to enter the recess in that end of the roll. Both sections can then be pressed together until the interlocking sections will have become overlapped and locked.

One form of preferred roll-actuated cam-lock-guard is best shown in Fig. 3 as consisting of a plate 45 having a lifting part, shown as a cam flange 46 at one end and a recess-engaging portion 47 at the other, the cam flange 46 and the recess-engaging portion 47 being capable of raising out of interfering position with respect to the roll only when the roll is of such construction that the projection 47 may enter a recess for its reception.

Such a roll 48 is illustrated in Fig. 5 as having recesses 49 and 50 from the inner circumference toward the outer circumference through a number of the sheets but preferably not entirely through the roll, the recesses being well within the roll distant from the ends thereof so that they will not

be visible nor readily accessible after the roll is in place, and such roll may be perforated to provide sheets as may be required, the perforations and recesses to be in alignment if desired, and the perforations extending through to the core and forming ends slits 36 and 37.

The roll is provided with the longitudinal end slit 36 to receive the centering finger or blade 34 which may be carried by a web portion 52 as part of the plate 45, and provided to determine the position of the roll so that the perforations can be placed only to the top with the recess 49 unfailingly in line to receive the recess-engaging portion 47, and if desired, a guard 53 may be struck up from the plate 45 and provided with a depending finger 54, which, when the lock-guard plate 45 is in the position shown in Fig. 1, will drop back of the shoulder 18 on the axle member 12 so that when the arms 3 and 4 are swung inwardly, the parts 18 and 19 cannot lock, the guard finger 54 being movable out of obstructing position only when the plate 45 is lifted and since the lifting can only be accomplished by a roll constructed similar to the one designated 48 in Fig. 5, it is obvious that an unauthorized roll of paper cannot be successfully employed, but it is apparent that even without the plate 45 having the depending finger 54, the recess-engaging portion 47 and the cam flange 46 will still exclude any roll not provided with internal recesses.

In the illustrated embodiment of my invention shown in Fig. 1, the recess-engaging blade or finger 47 is shown as projecting through a slot 55 in the end face of the mandrel member or drum 20, the lug 53 projecting through an opening 56 in the end face, and the centering or aligning finger 34 projecting through a longitudinal slot 56 in the perimeter of the mandrel member 20. The cam flange 46 extends through a corresponding opening 57 in the perimeter of the member 20 and substantially diametrically opposite to the slot 56.

Fig. 4 shows another form of lock-guard for use in the opposite mandrel section which carries the weight, and the roll 48 is provided with a recess 50 corresponding to the recess 49 to receive the roll-engaging portion 47. This opposite recess may be engaged by a swingable-lock-guard shown as consisting of a plate 58 having side edge flanges 59 and 60 with aligning perforations 61 and 62, which are adapted to receive a hinge or pivot member 63 which projects through the down-bent flanges 64 and 65 struck out from the peripheral surface of the member 21. The pivoted plate has an upstanding flange 66 at one end and a recess-engaging finger 67 at the other, the recess-engaging finger 67 being shown as

curved so that it will conveniently fit into the recess 50 when the roll is placed upon the mandrel member 21. The flange 66 has a slot 66' which is engaged by the guide 5 projection 35 struck inward from the mandrel flange 23 and provided to strengthen the swingable-lock-guard 58 and provided also to engage the roll end slit 37 to position the roll so that the line of perforations 10 can be placed only to the top with the recess 50 unfailingly in line to receive the recess-engaging finger 67.

When the mandrel member is being inserted into the core 68 of the made-up roll 15 48, the swingable lock-guards 58 will assume the position shown in Fig. 1, but when the member 21 has been introduced far enough so that the edge of the roll 48 contacts with the flange 66, the lock-guard 58 20 will be tilted into locking position as shown in Fig. 5, with the flange 66 resting in the plane of the mandrel flange 23, allowing the roll to enter fully onto the mandrel 21, but if a roll of improper construction were 25 applied, then the swingable lock-guard 58 could not take its proper position with the result that the roll would not be permitted to enter fully onto the mandrel and consequently the axle parts 18 and 19 could not 30 be brought together sufficiently to overlap and lock, and the whole would be inoperative.

If a roll of proper construction is thus placed upon the mandrel or core members 35 20 and 21 and the arms 3 and 4 are swung inwardly, the locking engagement of the parts 18 and 19 will be unopposed and they will move into the position shown in Fig. 2, the roll protecting the locking members 40 18 and 19 from access because as soon as there is a pull upon the free end of the paper, there will be a slight creeping of the paper about the axis of the roll whereby the slits 36 and 37 and the slotted perforations 45 will become somewhat staggered or overlap the corresponding slits in the inner layers of the roll so that the perforations and slits will assume the positions shown in Figs. 8, 9 and 10. Therefore, it 50 will be impossible to introduce a tool through the roll to pry the locking ends 18 and 19 apart, it being understood that the slits 36 and 37 and slotted perforations 55 69 originally assume aligning positions, as shown in Fig. 7, but as soon as tension is placed upon the paper, they assume the positions shown in Figs. 8, 9 and 10.

When the pull is exerted on the loose end of the paper roll, the entire mandrel consisting of the axle members 12 and 13 and the members 20 and 21, together with the roll, will be given a partial rotative movement against the action of the coil springs 38 and 39, the tensions of the springs increasing as the coils are wound and further

resilient retardation being offered by the contact of the fingers 32 and 33 against the flat springs 30 and 31 until the resilient fingers 24 and 25 come in contact with the resilient fingers 26 and 27 whereupon the 70 paper will be severed in pre-determined lengths, whether one sheet or more.

As soon as the paper is severed, the recoil springs will move the parts back to normal position as shown in Fig. 1. 75

In some instances it may be desirable to have an over-balance weight 70 in at least one of the members 20 or 21 and for convenience, I prefer to place the weight in the member 21 and so dispose it with relation to the center of gravity that the inertia of the weight, together with the return effect of the coil springs will be sufficient to cause the mandrel or drum member to over-recoil enough to bring the line of 85 severage, as indicated at 71 in Fig. 10, slightly beyond a vertical line 72 drawn through the axis of the roll, thus insuring that the free end of the paper will always drop, ready to be grasped when desired. 90

Under certain conditions, however, the weight may be dispensed with for it is possible to design the coil spring so that the over-recoil will be sufficient to drop the sheet. 95

When a roll has been depleted about two thirds or more and the layers of sheets have been torn off in use down to a point below the overlapping of the perforations indicated by the diagonal line 76, the attendant 100 when calling at any time to replenish and, without having to wait until the roll has been entirely used up, can proceed to remove the remnant by inserting a special wedge end tool through the perforations 69 105 down into the open space between the axle terminals 14 and 15 to pry them apart to disengage, and when using the fixture with the mandrel sections swung into position at right angles to the back of the bracket 110 and with the left mandrel supporting a depleted roll and the right mandrel supporting another partly used or a full roll, both rolls with their respective mandrels can be revolved at the same time without 115 slipping, and the remnant from the depleted roll can be saved instead of thrown away and can be rewound upon the outside of the partly used or full roll, and when this process is finished and the discard roll 120 core is removed, the rewound roll can be swung into the aligned position and locked in place for use as above described, but if preferred, the remnant can be hung upon the scrap hanger for further use as explained. 125

In Fig. 11 I have shown a detail view of a device adapted to be utilized for separating the axle members when the paper roll is nearly depleted. The particular construc- 130

tion of tool selected for illustrative purposes is shown as consisting of a shank 73 having a blade portion 74 and a handle or eye 75. The tool is so constructed that 5 when the roll is about depleted and the slits 69 in all of the sheets are in alignment, the blade 74 may be inserted through them and between a curved edge 16 or 17 and a shank of an opposing axle member 10 so that the tool may be manipulated to force the engaging ends of the axle members apart in an obvious manner. By reference to Figs. 1 and 2, it will be seen that the projections 25 are struck up 15 from the metal ends 22 and 23 so that they provide notches, the inner edges of which are co-incident with the drum perimeters 20 and 21. Therefore, the amount of paper remaining upon the roll can be at all times 20 determined by observing from either side of the drum heads.

My invention and the usefulness of same as thus described in this example is clearly disclosed and it is evident that construction may be modified without departing from the spirit of my invention and I, therefore, do not limit myself to the precise structure shown and described.

What I claim and desire to secure by Letters-Patent is:

1. A paper roll dispensing device comprising a wall plate, swinging arms on the wall plate, separable mandrel sections carried by the arms constituting a revoluble 35 roll holder, complementary separable axle sections carried by the mandrel sections, and means on the ends to lock the roll upon the roll holder, said mandrel sections having roll recess-engaging locking members with projecting ends adapted to engage recesses in the interior of said roll to prevent relative turning of the axle sections with reference to the roll and with reference to each other.
2. A paper roll dispensing device comprising a support, separable mandrel sections carried by the support and having swinging movement at angles one to the other, and swinging movement into aligning position, said sections constituting a roll holder to 45 receive a paper roll having a hollow core, said mandrel sections having complementary axle sections formed with ends provided with recesses, and shoulders for interlocking the axle sections together and within the 50 core of the roll supported by said roll holder, said axle sections having outwardly curved faces to facilitate engagement of said axle sections when swung into aligning positions and to facilitate disengagement of the axle 55 sections so that said mandrel sections may be swung from the aligned positions to positions at angles to each other.
3. In combination with a paper roll having perforations in its top sides extending 60 through to the core and formed with slits 65 in its ends, said roll having recesses along the line of said perforations and located within the core of the roll and distant from the ends thereof, of a roll holder to support said roll, said roll holder having locking 70 means to engage said roll recesses and said roll holder consisting of mandrel sections having roll guide inwardly-projecting members to engage the roll end slits to guide the placing of the roll upon the roll holder so 75 that the line of perforations will always be at the top with the said recesses in position to be engaged by the locking members.
4. A paper roll dispensing device comprising a roll holding mandrel consisting of interlocking sections, hinged supports for the sections to move them into and out of interlocking position, and means for normally opposing the interlocking engagement of the sections, said means being movable 80 out of functional position by the application of a roll upon the mandrel.
5. A paper roll dispensing device comprising a roll holding mandrel consisting of interlocking sections, hinged supports for 85 the sections to move them into and out of interlocking position, and means for normally opposing the interlocking engagement of the sections, said means being immovable out of functional position upon the 90 attempted application of a paper roll not having recess-engaging means to co-operate with the said opposing means.
6. A paper roll dispensing device comprising a mandrel consisting of interlocking sections, and means for normally opposing the interlocking engagement of the sections, said means being automatically movable out of 95 functional engagement only by the application to the mandrel of a paper roll having recess-engaging means to co-operate with the said opposing means.
7. A paper roll dispensing device having supporting means to fit into the hollow core of a paper roll, said roll having opposite recesses located within the core of the roll distant from the ends thereof, and separable mandrel sections carried by the supporting means having roll-actuated members to engage the said roll recesses.
8. A paper roll dispensing device having supporting means to fit into the hollow core of a paper roll, said roll having opposite recesses located within the core of the roll distant from the ends thereof, and separable 120 mandrel sections carried by the supporting means having locking members to engage the said roll recesses.
9. A paper roll dispensing device comprising a mandrel adapted to receive a paper 125 roll having recesses within the core thereof, spaced from the ends of the roll, a paper roll-engaging means carried by the mandrel having a recess-engaging finger, and a part engageable by the roll for actuating the 130

paper-engaging means to introduce the finger into the recess in the roll.

10. A paper roll dispensing device comprising a support, swinging arms carried by the support and having box-shaped ends providing journal bearings, mandrel journals in the bearings, mandrel heads carried by the journals to support a paper roll, means for causing interlocking engagement of the ends of the journals when they are brought together, a coil spring on each journal, one end of which is secured to its journal and the other to an arm, fingers projecting from the journals within the boxes, and flat springs within the boxes against which the fingers frictionally contact upon rotative movement of the journals.

11. A paper roll dispensing device comprising a wall plate, an arm on the wall plate, said arm having at its outer end a vertical box with spaced sides, a paper roll supporting axle journaled in the spaced sides of the box, and a retractive spring wound around the axle between the spaced sides of the box, one end of the spring being fastened to the box and the other to the axle to retractively revolve the axle and roll to a normal point beyond a center point of gravity.

30. 12. A paper roll dispensing device comprising a wall plate, outstanding arms carried by the wall plate and carrying boxes at their ends provided with spaced walls, resilient stop members on the inner faces of the arms, a spring-retractible, rotatable mandrel mounted in the arms in the boxes and comprising paper engaging heads, the springs for retracting the mandrel being located within the walls of the box and one end of each spring being fastened to a wall of its box and to the mandrel, and resilient stop fingers carried by the head rims and contactable with the resilient stop members on the arms upon rotation of the mandrel.

45. 13. A paper roll holder comprising outstanding arms having inwardly positioned projections and having a revoluble roll support adapted to enter the core of a paper roll and to automatically interlock with the roll; said roll support having a rim part cut away on either side forming an opening adapted to disclose the amount of paper remaining in the process of depletion and said cut rim part being bent outwardly, forming 55 a resilient projection designed to contact with the arm projection and thereby to stop at that point the further revolution of the roll support and the paper roll.

60. 14. In combination, a paper roll having a central longitudinal opening constituting a hollow core, the roll having openings spaced inwardly from its ends at right angles to and accessible from within the roll core, a roll support extending within the hollow core of the roll and having enclosed slots in

opposite sides with reference to the axis of the support, a lock guard slidably mounted in said slots and extending transversely entirely through the body of the roll support from one side through to and beyond the 70 opposite side, and a finger at one end of the lock guard submerged in one slot, the lock guard having an inclined portion at the opposite end resting in the opposite slot and protruding out from the surface of the roll 75 support, the lock guard being adapted to slide bodily by the application of the paper roll so that as the protruding inclined portion of the lock guard is forced by the roll inwardly within the roll support at one side thereof, the submerged finger at the other side is correspondingly protruded outwardly and into the roll opening and thus provides 80 interlocked engagement of the roll support with the paper roll.

85. 15. In combination, a paper roll having a central longitudinal opening constituting a hollow core, the roll having openings spaced inwardly from its ends at right angles to and accessible from within the roll core, a 90 roll support within the hollow core of the paper roll having enclosed slots in its opposite sides with reference to the axis of the support, a lock guard slidably mounted in said slots and extending transversely entirely through the body of the roll support from one side on through the opposite side and formed to present at one end a finger part that may rest submerged in one slot and at the other end an inclined part resting in the opposite slot and protruding from the surface of the roll support, said lock guard being adapted to be slid bodily by the application of the paper roll so that as the protruding inclined part of the lock guard 95 is forced inwardly within the roll support by the roll at one side thereof, the submerged finger at the other side is correspondingly protruded outwardly to engage the opening in the roll but so designed as 100 to obstruct the application of so-called foreign rolls not formed with means to receive the protruding finger end of the lock guard of the roll support.

115. 16. A roll support or paper rolls having a hollow core with openings spaced inwardly from the ends at right angles to and accessible from the core, said roll support comprising a member receivable within the hollow core, a lock guard slidably mounted in said member and extending transversely entirely through the same, and a finger at one end of the lock guard, the lock guard having an inclined portion at the opposite end protruding from the surface of the member, the lock guard being bodily slid- 120 able upon application of a paper roll so that the inclined part of the lock guard will be forced inwardly within the roll support by the roll at one side thereof and the finger at 125 130

the other side will protrude outwardly to engage an opening in the roll.

17. A roll support for paper rolls having a hollow core with openings spaced inwardly 5 at right angles to and accessible from the core, said roll support comprising a member receivable within the hollow core of the roll, a lock guard extending transversely entirely through the member from one side to and 10 beyond the opposite side, and a finger at one end of the lock guard, the lock guard having an inclined portion at one end protruding from the surface of the member, the lock

guard being adapted to slide bodily by the application of a paper roll so that the protruding inclined portion of the lock guard will be forced by the roll inwardly within the member, the finger being movable into the roll opening to provide interlocked engagement of the roll support with the paper 20 roll, the lock guard being so designed as to obstruct the application of so-called foreign rolls not formed with means to receive the finger end of the lock guard. 15

In testimony whereof I affix my signature. 25
ROCKWELL M. MACCORMAC.
